HORIZON GYRO

Bert G. Carlson, Erieside, Ohio, assignor to Jack & Heintz, Inc., Bedford, Ohio, a corporation of Ohio

Application January 16, 1943, Serial No. 472,609

2 Claims. (Cl. 74—5)

This invention relates in general to gyros and more particularly to erection devices therefor.

The primary object of the invention is to provide an improved gyro erection device that will be simple in construction and assembly and positive and efficient in operation.

To this end it is proposed to provide a cap rotatably mounted on the lower compartment of the gyro box to cover the air exhaust apertures and having an aperture to the atmosphere. Besides being rotatably mounted, the cap is provided with a weight arranged eccentrically and near the periphery of the cap. Any deviation of the gyro box with respect to the vertical results in the weight seeking the lower side and acting as a pendulum to bring about the erection of the gyro.

With the foregoing and other objects in view, the invention resides in the combination of parts and in the details of construction hereinafter set forth in the following specification and appended claims, certain embodiments thereof being illustrated in the accompanying drawing, in which:

Figure 1 is a view in elevation, partly in section of an horizon gyro assembly with the improved erection device, showing the gyro in vertical position;

Figure 2 is a view in cross section, taken along line 2—2 of Figure 1;

Figure 3 is a bottom plan view of the erection device; and

Figure 4 is a partial view in elevation of the gyro box and erection device with the gyro box slightly tilted to the left.

Referring more particularly to the drawing, Figure 1 shows an horizon gyro assembly in normal vertical position with a gyro wheel 1 having trunnions 2 engaging bearings 3 in a gyro box, the rotor compartment of which is indicated at 4. The box has suitable trunnions 5 to be carried by a suitable gimbal support. Coextensive with the rotor compartment 4 is a lower compartment 5 to the lower end of which is secured a plate 6 by means of screws 7.

As is usual practice, air is drawn in by suction through ports 8 to jets 9 to impinge on the rotor buckets 10. In order to evacuate this air after it has spent its force in spinning the gyro wheel, apertures 11 are provided to lead the air from the upper compartment 4 into the lower compartment 5, the lower plate 6 of which has a series of apertures 11.

Departing from the usual practice of employing a plurality of pendulum shutters for regulating the opening and closing of the exhaust ports, it is proposed to use a single exhaust port and a single

shiftable gravity responsive weight. To this end there is provided a cap 12 secured by a pin 13 to a spindle 14 which is mounted for rotation in bearing assemblies 15 and 16 in such a manner that the edges of plate 6 and cap 12 overlap to form a compartment 17. The cap 12 is provided with a single tangentially disposed aperture 20 so that as viewed in Figure 3 a rotation of cap 12 in a counterclockwise direction is imparted as air is exhausted from compartment 17.

Secured to cap 12 by a screw 18 is a weight 19 that is arranged eccentrically of spindle 14 and near the periphery of cap 12. In normal operation when the gyro is vertical the force of the air exhausting through the aperture 20 causes cap 12 and its weight 19 to rotate slowly in a counterclockwise direction. When, however, the gyro becomes tilted, the weight seeks the lower side of the tilt. This is illustrated in Figure 4 where the gyro is tilted to the left and the rotative force of the air exhaust through the tangential aperture 20, arranged at approximately ninety degrees to the weight, is insufficient to cause the weight to climb up the hill. The maintenance of this position by the weight causes a pendulous effect upon the gyro resulting in its becoming erected. When the erection is completed the cap resumes its normal slow rotation.

By this simple expedient the construction and assembly is greatly simplified and the operation dependable and efficient. This is because there is eliminated the provision of pendulum shutters which by reason of their hinges may not properly regulate their respective exhaust ports which latter may also become partially closed by sediment.

I claim:

1. In combination in a vertical axis gyro assembly including an air spun gyro and a casing therefor, a spindle rotatably mounted in bearings 40 in said casing below said rotor coaxially with the spin axis of said rotor, a cap secured to said spindle and forming a compartment in communication with said casing and provided with an air discharge outlet port in the periphery of said cap and at right angles to the axis of rotation of said rotor, said cap being adapted to be rotated by the discharge of air as said casing is being evacuated, a weight secured to said cap eccentrically of the axis of said spindle and adapted, 45 upon tilt of said gyro, to overcome the rotative force created in the chamber enclosed by said rotative cap and pendulously apply an erective effect upon said gyro assembly until said gyro is erected and automatically resume normal rotation when said erection is completed.

2. In combination in a vertical axis gyro assembly including an air spun gyro wheel and a casing therefor, said casing including an upper compartment for housing the wheel of said gyro and a lower compartment, a partition between said compartments and ports extending through the partition, a plate secured to the bottom of said lower compartment having ports extending therethrough, upper and lower ball bearing assemblies arranged respectively in said partition and plate and a spindle extending therethrough, a cap secured to the lower end of said spindle, said spindle having a shoulder resting on the inner race of said lower bearing assembly for sustaining the entire vertical load of said spindle and cap carried thereby, said cap and plate hav-

ing their inner faces spaced to provide an air chamber, an exhaust port in the periphery of the cap and in a plane at right angles to the axis of rotation of said gyro wheel, whereby an exhaust 5 of air through said port in said cap imparts a rotary motion to the cap, said cap having secured thereto on its lower surface a weight near its periphery and eccentric of the axis of rotation of its spindle, said weight being adapted, 10 upon tilt of said gyro, to overcome the rotative force created in the chamber enclosed by said rotative cap and pendulously apply an erective effect upon said gyro assembly until said gyro is erected and automatically resume normal rotation when said erection is completed.
